(57) **CLAIM**

The ornamental design for a fitness bag, as shown and described.

DESCRIPTION

FIG. 1 is a front perspective view of the fitness bag showing my new design.

FIG. 2 is a front view of the fitness bag.

FIG. 3 is a rear view of the fitness bag.

FIG. 4 is a left side view of the fitness bag.

FIG. 5 is a right side view of the fitness bag.

FIG. 6 is a top view of the fitness bag; and,

FIG. 7 is a bottom view of the fitness bag.

Any shading and cross-hatching are not features of the design but are utilized to illustrate the surface contours of the fitness bag design in the drawings.

The broken lines illustrate portions of the fitness bag that form no part of the claimed design.
